UNITED STATES PATENT OFFICE.

ARCHIBALD CULBERT AND JOHN L. CULBERT, OF NEW YORK, N. Y.

DESIGN FOR A FRONT FOR MAIL-BOXES.

SPECIFICATION forming part of Design No. 18,473, dated July 17, 1888.

Application filed May 25, 1888. Serial No. 275,081. Term of patent 7 years.

To all whom it may concern:

Be it known that we, ARCHIBALD CULBERT and JOHN L. CULBERT, citizens of the United States, and residents of New York, in the county and State of New York, certify that we have invented a certain new Design for a Front for Mail-Boxes, Speaking-Tubes, and Bell-Cranks, of which the following is a specification.

10 The nature of our design is fully represented in the accompanying engraved perspective view of our newly-designed front, forming a part of our specification.

Our design for a mail-box front embraces as 15 the main distinguishing feature a rectangular frame-work surmounted by an ornamental speaking-tube mouth-piece. The sides of the ornamental frame-work consist, mainly, of fluted pilasters *a* and egg and dart molding 20 *b*, and the top and bottom portions, *c* and *d*, are of ornamental carved molding, as shown. Above the frame-work is placed the speaking-tube mouth-piece *e*, on both sides of which are placed representations of griffins, *f*, and over 25 which is the ornamental carved top piece, *g*, and beneath which is the medallion *h*. An ornamental partition, *m*, divides the inclosed

space within the frame-work into two panels, the lower one being provided with an ornamental central opening, *o*, and a recess for a name-plate, *p*, and a circle, *q*, surrounding the lock, the openings *o*, *p*, and *q* being inclosed in a richly-embellished frame-work, *r*, without and below which are placed ornamental leaves and fruit, *s*, and on the sides of the upper part 35 of which are carved leaves and flowers, *t*, terminating in griffins' heads *v*.

What we claim is—

The design for a mail-box front herein set forth, consisting of the rectangular carved 40 frame-work *a b c d*, containing the embellished frame *r*, set in carved work *s t u* and surrounded by the ornamental carvings *f g h*, surrounding the mouth-piece *e*.

In testimony of the foregoing specification 45 we do hereby sign the same, in the city of New York, county and State of New York, this 23d day of May, A. D. 1888.

ARCHIBALD CULBERT.
JOHN L. CULBERT.
